UNITED STATES PATENT OFFICE.

GUSTAV WEGNER, OF BAUDETTE, MINNESOTA.

DOOR-LOCK.

1,297,616.

Specification of Letters Patent. Patented Mar. 18, 1919.

Application filed March 24, 1917. Serial No. 157,171.

To all whom it may concern:

Be it known that I, GUSTAV WEGNER, a German subject, residing at Baudette, in the county of Beltrami and State of Minnesota, have invented certain new and useful Improvements in Door-Locks, of which the following is a specification.

This invention relates to an improvement in door locks and more particularly to a lock of this character of the combination or permutation type.

An object of my invention resides in providing means by which the bolt securing means can be set to positively secure the bolt against release even by manipulation of the combination parts, may be shifted to a second extreme position to release the bolt securing means so that the lock may be used after the manner of an ordinary spring latch, and is further adjustable to a position intermediate between the two extremes in which the parts will operate after the manner of a night latch and when the bolt has been thrown, it may be released by proper manipulation of the combination means from the outer side of the door.

With the above and other objects in view, which will be in part described and in part understood by the specification, drawings, and claims, my invention consists in certain novel features of construction and combination of parts which will be hereinafter more fully set forth.

In the drawings:-

Fig. 1 is a view in elevation showing the lock structure as the same would appear before application to a door;

Fig. 2 is a transverse vertical sectional view taken substantially through the center of the lock structure;

Fig. 3 is a vertical sectional view taken longitudinally through the casing and substantially on the line 3-3 of Fig. 2; and,

Fig. 4 is a horizontal longitudinal sectional view taken on the line 4-4 of Fig. 3.

The lock structure proper is contained within a casing 1 which is adapted to be secured on the inner side of a door or within a mortise formed on the inner side, and to be held in place by means of screws or other suitable fastenings passed through the openings 2, and this casing 1 has a sleeve 3 formed to extend from that side which is to be placed against the door, the sleeve thus being so arranged that an opening must

be provided through the door for the reception thereof, and the sleeve thus opens on the outer side of the door. However, it is desirable that a cover plate 4 be provided on the inner side of the casing 60 and be removable to permit access to be had to the interior of the casing.

The forward edge of the casing 1 has an opening 5 formed therethrough for the reception of the bolt 6, which bolt at its outer end is beveled diagonally across to take the form of the bolt of a spring latch, and the inner end of the bolt 6 is provided with a slotted opening 7 through which the pin 8 carried by the casing passes to thus hold the bolt to have sliding movement in a fixed path. A leaf spring 9 is caught under a hook 10 provided in the casing and is swung outwardly by a lug 11 so that it bears against the inner end of the bolt 6 and thus resiliently forces the bolt outwardly to such a position that further movement is limited by abutment of the pin 8 against the inner end of the slotted opening 7. A bolt releasing member 12 is 80 suitably mounted in bearing openings provided in the casing and in the cover plate 4 so that it is disposed adjacent the bolt 6 and a finger 13 is provided on this bolt receiving member to be loosely fitted in the opening 14 formed in the bolt, so that as the bolt releasing member is turned in a counter-clockwise direction, as the parts are illustrated in Fig. 3, the bolt 6 will be withdrawn against the tension of the leaf spring 9 and the beveled end will be retracted into the casing. The bolt releasing member 12 is provided with a squared opening or an opening of other polygonal form, for the reception of the knob spindle 15, and the knobs 16 and 17 are provided on the ends of this spindle to be disposed on the outer and the inner sides of the door.

With the parts arranged in the manner as set forth, a structure is provided which to all intents and purposes is substantially identical with the usual form of spring latch, and without additional restraining means the parts will operate very efficiently in this capacity. However, some means must be provided to hold the bolt in the thrown or locked position, and to accomplish this purpose I mount a leaf spring 18 on the inner side of the casing to extend substantially parallel with the length of the 110

bolt and with its free end disposed to normally bear against the inner side of the bolt. The bolt shank is notched as shown at 19, and when the spring 18 has unrestrained movement, it moves to engage at its free end behind the shoulder formed by the notching of the same and thus positively locks the bolt against being withdrawn through turning of the knobs 16 or 17. To adapt the bolt and the lock structure for use upon doors closing either inwardly or outwardly, it is of course essential that the bolt 6 be reversible, to dispose the beveled side of the end thereof properly, and with this purpose in view, I provide a notch 20 on the opposite side of the bolt shank corresponding in its position to the location of the notch 19 and shape the opening 14 to present an equally operative form on both upper and lower sides of the shank. To change the bolt, it is only necessary to remove the cover plate 4, and then raise the bolt 6 from the position in which it is fitted within the opening 5 and over the pin 8, following which the bolt 25 is turned over or reversed and is again fitted in the same position.

It will of course be understood that under normal conditions the spring 18 will be engaged within the notch 19 or 20, and will hold the bolt 6 positively against movement to the released position, and as the combination means, which will be hereinafter more fully described is intended for opening of the lock only from the outer side of the door, it is essential that some means be provided to release the spring 18 from that side of the door on which the casing 1 is mounted, and it is preferable that the means be so constructed that the spring 18 can be positively locked in the bolt securing position and can be left free to act through its own resiliency. With the above in view, I mount a shaft 21 between the inner side of the casing 1 and the cover plate 4 and provide thereon what might be designated as a tripping member 22, which is made up of the spokes radiating from a hub mounted on the shaft 21 and a split rim. The split rim is so shaped at the free end that one end is bent outwardly as shown at 23 whereas the other end is bent inwardly as indicated at 24, and thus when the tripping member 22 is mounted with the main portion of the rim substantially in line with the free end of the spring 18, the spring will be received between the ends 23 and 24 and will then be free to act on its own natural resiliency, or when the tripping member is turned in one direction or the other the spring will be shifted under the exertion of a cam action thereagainst by either the ends 23 or 24 in accordance with the direction in which the member 22 is turned. The rim extends through the upper side of the casing 1 and is roughened as shown at 25, a pin or other suitable stop 26

being provided to determine and limit the movement of the tripping member to its extreme positions and also to indicate the setting of the spring 18 in the intermediate position or where the spring 18 is free to move 70 into and out of engagement with the sliding bolt. When the tripping member 22 is turned in a clockwise direction, as the parts are illustrated in Fig. 3, the end 24 thereof will engage with the spring 18 on that side 75 which is adjacent the bolt 6 and in consequence the spring 18 will be forced out to be disengaged from the notch in the shank of the bolt in which relation the spring will be positively held until the tripping member is 80 again shifted. Upon turning of the tripping member in the opposite direction or in a counter clockwise movement, the end 23 engages on the opposite side of the spring 18 and forces the same inwardly to positively 85 lock the spring against movement to a position that it may be disengaged from the notch to the bolt, and of course it will be understood that when the parts are as shown in Fig. 4, the spring 18 can be freely moved 90 from the notch. As has been stated, it is preferable that the extending portion of the tripping member 22 be roughened to give a better surface for manual manipulation thereof, and the stop 26 will of course act 95 as a guide in the setting of the parts.

In the foregoing I have described the spring latch mechanism of the lock together with the means for securing the bolt in the sprung or locked position, and also means 100 for controlling the spring by which the bolt is locked, and it will be understood that where the lock mechanism is to be used as a spring latch and is to be locked only from the inside of the door, these parts would doubtless prove sufficient, however, it is a purpose of my invention to provide combination means by which the spring 18 can be moved to the inoperative position or to a relation in which it is disengaged from the bolt 6 to thus 110 permit the knob 16 to be turned and the bolt to be withdrawn. As has been stated, the sleeve 3 is disposed from the casing 1 to open at its outer end on the outer side of the door, and this sleeve will be made of such length 115 that it will terminate flush with the outer surface of the door, this being readily accomplished as standard doors are generally made to be of one and three-eighths or one and three-fourths inches in thickness. Combination dials 27, 28, and 29, of which three are shown in the present illustration but of which there might be a greater or lesser number, are each made of successively smaller size, and the dial 27 has a bearing 120 sleeve 30 formed to extend from the inner side thereof and made of such a size that it will have a bearing engagement within the sleeve 3 of the casing, the dials 28 and 29 each being provided with the bearing sleeves 125 130

31 and 32 which are made of successively smaller size and are telescoped or interfitted to be capable of turning movement. By mounting the parts so that the bearing sleeve 5 30 is within the sleeve 3 with the sleeves 31 and 32 interfitted, the combination dials 27, 28, and 29 are so disposed that the dial 28 shows a rim projection beyond the edge of the dial 29 whereas the dial 27 extends 10 around the periphery of the dial 28. Permutation disks 33, 34, and 35 are made to be of the same dimensions and are each provided with a notch 36 formed in the periphery thereof, as shown in Fig. 2, and these 15 disks are provided with central bores of greater size than the diameter of the respective sleeves which support the same for preventing wear upon edges of the bore thereof. The length of the sleeves 30, 31, and 32, is 20 so regulated that the thickness of the disks 33, 34, and 35 is compensated for and screws 37 are provided to be set in the ends of the sleeves 30, 31 and 32, to bind against the permutation disks 33, 34, and 35 to secure 25 these disks in predetermined settings with respect to markings on the faces of the combination dials 27, 28, and 29, and which markings will be more fully described hereinafter. By loosening the screws 37 so that 30 the heads thereof are out of binding engagement with the permutation disks, the disks may be turned to vary the disposition of the notches 36 and then the screws can be again tightened to lock or secure the disks against 35 accidental or further shifting. Any suitable dial markings may be placed upon the combination dials 27, 28, and 29, however, to make it possible to easily remember when the combination notches 36 of the permutation 40 disks are registered, the combination dial 27 might be divided off and have the various divisions thereof indicated by notation of years, or multiples of years, with sub-divisions to represent intermediate years, the 45 disk 28 could have the edge divided off and designated by notation of the months of the year, and the dial 29 might be divided off into thirty divisions and marked with numbers designating the days of the month, and 50 then in setting the permutation disks so that the notches thereof correspond with the desired numbers on the combination dials the day, month, and year of the birth of the party who will make use of the combination, 55 could be used as a key, and thus the combination would be one to be very readily remembered.

The central opening of the sleeve 32 opens 60 at its outer end through the dial 29 and at its inner end through the disk 35, thus forming a direct passage into the casing, and a spindle 38 is disposed through this central bore or opening to be capable of turning as well as endwise slidable movement. This 65 spindle 38 has a dial 39 on the outer end thereof and a handle 40 is provided upon the disk so that the dial together with the spindle 38 can be turned or moved longitudinally in either direction through the central bore of the sleeve 32. This spindle 38 is made of 70 greater length than the bore of the sleeve 32, the increase in length corresponding substantially to the combined thickness of the permutation disks 33, 34, and 35, and at its inner end the spindle is reduced to form a 75 shank 41, which is screw threaded at its extremity. A bar 42 is provided with an opening to be received over the shank 41, and a nut 43 is provided to be tightened against the bar to hold the same in predetermined 80 settings upon the shank 41. This bar 42 has a plate or bit 44 carried at one end thereof and made of such a size and shape that it will pass into the notches 36 of the several permutation disks when the same have been 85 brought to registry, and the plate or bit further has an extension 45 which projects beyond the edges of the permutation disks. The spring 18 is disposed to extend from beneath the bolt 6, or it might be provided 90 with an extension as shown at 46 in Fig. 3, and thus as the several permutation disks are brought to a position that the notches are registered adjacent this extension 46 and the bar 42 is moved to a position that the 95 plate or bit 44 carried thereby will slide into the registering notches, outward pulling pressure exerted upon the handle 40 will cause the bit 44 to pass into the notches of the permutation disks and the bit will then 100 exert a displacing force against the spring 18 to move the same over from engagement with the notch of the bolt 6 after which the bolt may be withdrawn by turning the knob 16. To further increase the difficulty in 105 manipulating the parts to secure the proper combination, stops or checks 47 and 48 might be provided to extend from the inner side of the casing 1 in such relation that only 110 a narrow space is left through which the bit 44 can be drawn inwardly to exert the releasing force against the spring 18 or the extension as formed thereon. It will of course be understood that when the tripping member 22 has been shifted to bring the end 115 23 thereof against the spring 18, the spring will be positively locked and held in its engagement in the notch of the bolt 6, and even though the combination may be properly worked and the extension 45 of the bit 120 44 may be brought against the spring 18, the lock cannot be operated from the outer side of the door and such operation cannot be accomplished until the switch member 125 has been adjusted to release the spring 18 from its securement.

I claim:

1. A door lock comprising a casing, a bolt carried thereby, a locking spring adapted to engage and lock the same, a sleeve carried 130

- 4
- by said casing, a plurality of permutation disk supporting sleeves mounted therein, dials carried by said sleeves, disks supported upon the inner ends of said sleeves, said 5 disks provided with notches formed therein, a releasing bar, a spindle carrying said bar and passing through said sleeves, said bar provided with a bit adapted to fit in said notches and engage said spring for forcing 10 the same out of engagement with said bolt.
2. A door lock comprising a casing provided with a sliding bolt, a locking spring adapted to engage said sliding bolt for holding the same in a set position, a tripping 15 member carried by said casing and adapted to engage said spring for holding the same in a locked or unlocked position, a plurality of permutation disks mounted within said casing, a releasing bar coöoperating with said disks, a bit formed upon said releasing bar, said disks provided with notches formed therein adapted to be brought into registration with each other, said notches adapted 20 to receive said bit, said bit provided with means for engaging said locking spring for moving the same out of engagement with 25 said bolt when said tripping member is in

an open position, and means for facilitating the operation of said releasing bar.

3. A lock of the class described comprising 30 a casing, a plurality of sleeves carried thereby, a releasing bar, a plurality of permutation disks carried by said sleeves, each disk comprising a flat body provided with a central bore of greater diameter than the 35 sleeve which supports the same, a plurality of screws carried by the respective ends of said sleeves and overhanging the edges of said bores for adjustably and firmly holding 40 said permutation disks in engagement with the respective sleeves, dials carried by said sleeves for determining the position thereof, a sliding bolt, a locking spring engaging said bolt, and means carried by said releasing bar and coöoperating with said permutation disks for moving said locking spring 45 out of engagement with said sliding bolt.

In testimony whereof I affix my signature in presence of two witnesses.

GUSTAV WEGNER.
